UNITED STATES PATENT OFFICE.

OSCAR A. YOUNG, OF WEST BLOOMFIELD, NEW YORK.

FARM-GATE.

SPECIFICATION forming part of Letters Patent No. 243,339, dated June 21, 1881.

Application filed May 2, 1881. (No model.)

To all whom it may concern:

Be it known that I, OSCAR A. YOUNG, a citizen of the United States, residing at the town of West Bloomfield, in the county of Ontario and State of New York, have invented 5 certain new and useful Improvements in Farm-Gates; and I do hereby declare that the following is a full, clear, and exact description of the same, reference being had to the annexed 10 drawings, making a part of this specification, and to the letters and figures of reference marked thereon.

Figure 1 of the drawings is a perspective view of a sliding and swinging gate embodying 15 my invention. Fig. 2 is a perspective view, on an enlarged scale, of the hanger; and Fig. 3 is a sectional view of the same.

The present invention has relation to certain 20 new and useful improvements in that class of farm-gates adapted to slide horizontally and swing around at right angles to open the passage-way.

The invention consists in the peculiar construction of the hanger and manner of supporting 25 the gate thereon, as illustrated in the drawings, and hereinafter described.

In the drawings, A represents the gate, of the ordinary form and construction, and B C the two outer posts. The post B has formed 30 upon its inner side a vertical recess, a, to receive one end of the gate A when closed, thereby holding it stationary and from lateral displacement while engaged with said recess. The opposite post, C, has connected to it, near 35 its upper end, a flanged roller, b, for supporting the upper rail, c, of the gate, and also a latch, d, is secured to the post, with which engages the rail e. The flange on the roller b and the latch d hold the gate in the same horizontal line with the posts until raised sufficiently to disengage the rails with the roller and latch, when the gate may be swung around at right angles to its former position.

Between the posts B C is located a third 45 post, D, which divides the space between the two end posts into a passage-way for vehicles and pedestrians. The post, near its upper end, has connected to it a right-angle arm, f, upon which rests the upper rail, c, of the gate, and 50 below this arm are connected to the post two

pintles, g, a sufficient distance apart to receive the eyes h upon the rear side of the hanger E. This hanger is formed of a single piece of metal by being cast in a suitable mold in the ordinary manner, said hanger having upon its inner sides ways i, between which the journals of the roller k rest. The sides of the hanger E extend up above the periphery of the roller k to form guides l for the rail m of the gate, and project below to form guides n for the 60 rail e, thereby not only steadyng and guiding the gate on a horizontal line above the roller k, but below it, this being very important and essential in preventing too great a lateral strain on the hanger and the pintles. 65

Midway between the eyes h are flanges r, which prevent the hanger E being disconnected from the pintles, without the hanger is in such position as to bring the space between the flanges on the same vertical line with the 70 pintles. In this position the hanger may be raised off the pintles and the gate removed for repairs or other purposes.

It is important that some provision should be made whereby the gate will not become accidentally detached from the post D by the careless opening and closing of it, and at the same time in providing such means not to increase the cost in the construction of this class of gates. This, it is believed, has been 75 successfully accomplished by simply providing the hanger with the flanges r, arranged so that the space between them will come on the same vertical line with the holes in the eyes h. Should the gate A be swung around at an 80 angle, however slight, the flanges r, if the gate is raised, would strike against the under side of the upper one of the pintles g, thus preventing the gate being elevated to such extent as would disengage the eyes h with the 85 pintles g.

The eyes h, flanges r, guides l n, and ways i are all cast and formed together in the same mold, thereby not increasing the cost of manufacture, and obtaining a very practical and 90 durable, as well as effective, hanger for farm-gates.

Having now fully described my invention, what I claim as new, and desire to secure by Letters Patent, is—

The gate A and posts B C, in combination with the post D, having pintles *g*, and the hanger E, carrying roller *k*, the sides of said hanger extending to form guides *l n*, and having eyes *h* and flange *r*, substantially as and for the purpose set forth.

5 In testimony that I claim the above I have

hereunto subscribed my name in the presence of two witnesses.

OSCAR A. YOUNG.
